UNITED STATES PATENT OFFICE.

LAWRENCE J. ZAHN, OF ASTORIA, NEW YORK, ASSIGNOR TO THE INTERNATIONAL POSTAL SUPPLY COMPANY, A CORPORATION OF NEW YORK.

PRINTING MECHANISM.

Application filed September 25, 1922. Serial No. 590,255.

To all whom it may concern:

Be it known that I, LAWRENCE J. ZAHN, a citizen of the United States, and a resident of Astoria, county of Queens, and State of New York, have invented a certain new and useful Improvement in Printing Mechanism, of which the following is a specification.

This invention relates to printing mechanism and more particularly to a machine for endorsing checks or for like purposes having a rotatable printing cylinder, check feeding means, and means automatically controlled by the checks to effect a single revolution of the printing cylinder for each check passing through the machine, such for instance as that shown in the pending application of William F. Muller, filed July 28th, 1922, Serial No. 578,272.

The primary object and purpose of the present invention is to simplify and improve the construction and arrangement of the operating gearing for the feeding mechanism and the impression roll and printing cylinder so as to obtain a more direct transmission of the power from the driving motor and thereby render the operation of the several parts more positive and at the same time materially reduce the manufacturing cost of the machine.

It is another object of the invention to provide an improved mounting and arrangement of the electric motor and the driving connection between said motor and the primary transmission shaft of the operating mechanism.

With the above and other objects in view, the invention consists in the improved printing mechanism and in the form, construction and relative arrangement of its several parts as will be hereinafter more fully described, illustrated in the accompanying drawings and subsequently incorporated in the subjoined claims.

In the drawings wherein I have illustrated one practical embodiment of the invention and in which similar reference characters designate corresponding parts throughout the several views:

Figure 1 is a side elevation illustrating one embodiment of the invention;

Figure 2 is a horizontal section taken on the line 2—2 of Figure 1;

Figure 3 is a transverse section taken on the line 3—3 of Figure 1;

Figure 4 is a section taken on the line 4—4 of Figure 3;

Figure 5 is a transverse section taken on the line 5—5 of Figure 4;

Figure 6 is a detail elevation showing the mounting and arrangement of the housing for the operating gears of the printing couple;

Figure 7 is a detail section taken on the line 7—7 of Figure 2, and

Figure 8 is a sectional view taken on the line 8—8 of Figure 7.

In the illustrated embodiment of my invention I have shown the same as applied to an endorsing or cancelling machine for checks, certificates or other papers which in many respects is similar to the mechanism illustrated and described in the pending application above referred to.

The motor and operating gearing for the several active instrumentalities is mounted in a suitable housing or casing consisting of spaced side plates 5 connected by tie rods 6 and mounted upon a suitable base 7. The several parts of the gearing are covered and protected by the hinged top plate 8.

The operating parts of the machine include the printing couple consisting of a type carrying cylinder or die 9 which is removably secured upon one end of a driving spindle 10 which projects beyond one of the side plates 5. Beneath the spindle 10, a shaft or spindle 11 is rotatably supported in a bracket 12 which is fixed upon a rockshaft 13 journaled at its opposite ends in the side plates 5. Upon the end of the shaft 11 which projects exteriorly of the frame a rubber covered impression roller 14 is secured. The shaft 11 and one of the bearings for said shaft on the bracket 12 are vertically movable in a slot 15 provided in the side plate 5 through which said shaft extends. A coil spring 16 connected to the bracket 12 yieldingly holds the impression roller 14 in its normal position with respect to the printing cylinder 9. The pressure of the roller 14 against the paper check in opposition to the pressure of the printing cylinder on said check may be suitably regulated by the adjustment of the stop rod 17 in the transverse bar 18 connecting the side plates 5.

Upon the spindle 10 of the printing cylinder a sleeve 19 is loosely mounted and is

provided at one of its ends with a gear 20. The opposite end faces of this sleeve are recessed to receive friction discs 21. With one of these discs the opposed end of a 5 second sleeve 22 fixed upon the spindle is engaged. At the opposite end of the sleeve 19 a collar 23 is disposed upon said spindle and has a diametrically extending pin 24 movable in a longitudinally elongated slot 10 in the spindle. A nut 25 is threaded upon the end of the spindle and a spring 26 is interposed between said nut and the collar 23. By the adjustment of the nut 25 the pressure of the spring 26 acting to force 15 collar 23 into frictional contact with the disc 21, may be controlled and regulated. The collar 25 may be rigidly fixed in its adjusted position by means of a suitable set screw 27. It will also be apparent that the 20 pressure of the spring 26 acts to hold the opposite end of the loosely mounted sleeve 19 in close frictional contact against the other disc 21, which in turn urges said disc tightly against the end of the fixed sleeve 25 22. Thus it will be apparent that when the spindle 10 is free or no resistance is applied thereto, the sleeve 19, the sleeve 22 and said spindle will rotate as a unit. When, however, the fixed sleeve 22 and consequently, 30 the spindle 10 are held against rotation, the sleeve 19 will rotate loosely on the spindle. As the means for automatically controlling the rotation of the spindle 10 carrying the printing cylinder constitutes no part of the 35 present invention and is fully described in the pending application of William F. Muller, above referred to, it will not therefore be further described in detail.

The feeding mechanism for the checks or 40 other paper slips is also similar to that shown in said pending application. For the purposes of the present explanation it will suffice to state that the checks are arranged in a pile upon the supporting and guiding plate 45 28 and are fed forwardly over said plate by a rubber covered roller 29 fixed upon the shaft 30 beneath a presser foot 31. This presser foot is carried by the shaft 32 upon which a rubber covered roller 33 is fixed, 50 said shaft being vertically movable in a slot 34 in the side plate 5 as the presser foot is vertically adjusted relative to the plate 28 by any suitable means. The inner end of said shaft is mounted in an arm 35 fixed upon a rockshaft 36 journaled in the frame plates 5. Beneath the plate 28 a rubber 55 covered feed roller 37 is fixed upon the outer end of the shaft 38 which is arranged in vertical alignment with the shaft 32, said 60 roller 37 operating to feed the lowermost paper check or slip forwardly between a pair of upper rubber covered rollers 39 and an opposed pair of lower metal rollers 40, said lower rollers being fixed upon the

outer end of a shaft 41. These rollers 39 65 and 40 continue the forward movement of the paper check between the printing cylinder 9 and the impression cylinder 14. The mechanism above described is operated by means of an electric motor 42 which is suitably secured upon the underside of a plate 70 44 loosely hung from the shaft 30 by suitable bearings 45. The plate 44 extends longitudinally above the motor shaft 46 and is provided on its other end with a suitable 75 housing 47 through which the shaft 41 extends. The motor shaft 46 is journaled in the lower side of the housing and is provided with a worm 48 which is engaged with the worm gear 49 fixed on the shaft 41. 80

As seen in Figure 7 of the drawings, the motor shaft may be made in two sections, one of which is provided with a worm 48, said worm section being rigidly coupled to the other section of the motor shaft by the 85 sleeve 50 upon which adjacent to the motor case, a fan 51 may be secured so as to prevent over heating of the motor by maintaining a constant circulation of air throughout the interior of the case. It will thus be seen that the operating motor is suspended with its shaft in an obliquely inclined position from the spaced shafts 30 and 41. 90

Upon the shaft 41 a gear 52 is fixed and 95 meshes with a revising gear 53, which in turn is engaged with a gear 54 on the inner end of the shaft 11 whereby the impression cylinder of the printing couple is rotated in the proper direction. This inner end of the 100 shaft 11 and the shaft of the reversing gear 53 are journaled in the opposite side walls of a housing 55 which is also loosely mounted upon the shaft 41 and encloses the gear 52. The openings in the housing walls which 105 receive the shaft 11 are slightly elongated horizontally as indicated at 56 in Figure 6 of the drawings so that in the vertical movement of the shaft 11 the housing 55 may freely swing or rock upon the shaft 41. 110

Exteriorly of the housing 55 a relatively large gear 57 is fixed on the shaft 41 and is in constant meshing engagement with the gear 20 on the loosely mounted sleeve 19. An additional smaller gear 58 is also secured upon the shaft 41 and engaged with a large gear 59 on the stud shaft 60 fixed in one of the frame plates 5. This gear 59 transmits rotation to the gear 61 fixed on the shaft 38. The smaller gear 62 secured upon this shaft meshes with a gear 63 mounted upon a stud shaft 64, which connects the arms 65 and 66 loosely engaged upon the shafts 38 and 32 respectively. Rotation is transmitted to the shaft 32 from the gear 63 120 by means of the gear 67 which is fixed upon said shaft 32. 125

The shaft 30 of the feed roller 29 has a

gear 68 fixed thereon in mesh with the relatively large gear 69, which is engaged with the gear 61.

Through the medium of the gearing above described, it will be seen that the several active instrumentalities of the feeding and printing mechanism are operated in the proper directions so that the paper checks or slips are singly fed in an automatic manner to the printing couple where they are stamped or marked. The relative mounting and arrangement of the several gear elements with the motor provides a very compact arrangement of the operating mechanism and by utilizing a worm gearing connection between the motor shaft and the operating shaft 41, a very positive transmission of power from the motor to the several active parts of the mechanism is obtained.

For the purpose of absorbing vibration, preferably provide a coil spring 70 connecting the motor supporting plate 44 with one of the tie rods 6.

Ink is supplied to the type face of the printing cylinder 9 by means of a suitably mounted inking roller 71 which may be properly adjusted so as to exert the desired pressure upon the printing type. Also the machine is equipped with the usual counter 30 actuated from the shaft 10 through the medium of a star wheel 73 engaged by a pawl 74 on said shaft. However, this of course, is not an essential feature of the invention as any other operating means for the counter might be provided.

From the foregoing description considered in connection with the accompanying drawings, the construction, manner of operation and several advantages of my invention may be clearly and fully understood. By reason of the greater simplicity and compactness in arrangement of the motor and operating gearing, lost motion between the several parts is reduced to a minimum and a more positive and efficient transmission of power to the various parts is obtained. It will also be apparent that due to the reduction in the number of gear elements, the machine may be produced at appreciably less cost than prior machines of this type.

While I have herein shown and described a preferred embodiment of the invention, it is nevertheless to be understood that the same is susceptible of considerable modification in the form, proportion and relative arrangement of the several parts and I, therefore, reserve the privilege of resorting to all such legitimate changes as may be fairly embodied within the spirit and scope of the invention as claimed.

I claim:

1. In a printing mechanism, spaced shafts each actuating an active element of the mechanism, and an operating motor suspend-

ed from said shafts and having its shaft directly geared to one of the first named shafts.

2. In a printing mechanism, spaced shafts each actuating an active element of the mechanism, an operating motor suspended from said shafts and having its shaft directly geared to one of the first named shafts, and a housing enclosing said gearing and providing a bearing for the motor shaft.

3. In a printing mechanism, spaced feed roller shafts, an operating motor suspended from one of said shafts and having its shaft directly geared to the other of the first named shafts, and gearing connecting said feed roller shafts with each other.

4. In a printing mechanism, spaced feed roller shafts, an operating motor suspended from said shafts and having its shaft directly geared to one of the first named shafts, and a housing through which the latter shaft extends enclosing said gearing and providing a bearing for the motor shaft.

5. In a printing mechanism, spaced shafts each actuating an active element of the mechanism, a supporting plate loosely mounted at one of its ends upon one of said shafts, a housing on the other end of said plate through which the other of said shafts extends and in which the motor shaft is journaled, and gearing within the housing connecting the latter shafts to each other.

6. In a machine of the class described in combination with a printing cylinder and an adjustable impression cylinder, an operating motor, a shaft directly geared to the motor shaft, gearing connecting said shaft with the printing cylinder, additional gearing transmitting rotation from said shaft to the impression cylinder in a reverse direction to the rotation of the printing cylinder, and a housing for said gearing loosely mounted for rocking movement upon said first named shaft.

7. In a machine of the class described, in combination with a printing cylinder and an adjustable impression cylinder, an operating motor, a shaft directly geared to the motor shaft, gearing connecting said shaft with the printing cylinder, additional gearing transmitting rotation from said shaft to the impression cylinder in a reverse direction to the rotation of the printing cylinder, a housing for said gearing loosely mounted for rocking movement upon said first named shaft, a feed roller shaft, and a gear train connecting said first named shaft to the feed roller shaft.

8. In combination with a feed mechanism and a printing couple having a printing cylinder and an adjustable impression cylinder, an operating motor suspended from spaced shafts each actuating an active element of the feeding mechanism, gearing operatively connecting one of said shafts with the print-

ing cylinder, a housing loosely engaged for rocking movement upon said shaft and through which the shaft of the impression cylinder extends, gearing enclosed by said housing for transmitting rotation from the first named shaft to the shaft of the impression cylinder, worm gearing directly connecting the motor shaft to said first named shaft, and an additional gear train connecting said spaced shafts of the feeding mechanism to each other.

9. In combination with a feeding mechanism and a printing couple having a printing cylinder and an adjustable impression cylinder, a plate loosely provided at its opposite ends upon spaced active shafts of the feeding mechanism, said plate at one of its

ends being provided with a gear housing, a motor case suspended from the opposite end of said plate, the shaft of the motor being 20 journaled in said gear housing, worm gearing in said housing connecting the motor shaft with one of said active shafts, additional gearing connecting the latter shaft with the printing cylinder and impression 25 cylinder to rotate said cylinders in relatively opposite directions, and a gear train connecting the spaced active shafts of the feeding mechanism to each other.

In testimony that I claim the foregoing 30 as my invention, I have signed my name hereunder.

LAWRENCE J. ZAHN.
